DOOR LOCKS

Wilfred A. Beauchamp, Chicago, Ill., assignor to The Youngstown Steel Door Company, Cleveland, Ohio, a corporation of Ohio

Application July 31, 1956, Serial No. 601,179

10 Claims. (Cl. 268—44)

This invention relates to door locks and more particularly to locks for sliding doors of railway house cars.

It is an object of this invention to provide locks for sliding doors which shall engage the rear of such doors to secure them in closed position.

A further object is to provide locks of the character described above which shall be disposed between the lower and upper edges of the doors.

A further object is to provide locks for sliding doors engageable with the rear of such doors which shall lie behind them when the doors are open and embody means for retaining the locking member thereof in retracted position to avoid damage to the locks and doors.

A further object is to provide locks for sliding doors which shall engage the rear of such doors to secure them in closed position and which shall embody cooperating members capable of taking up slack created by the movement of the doors in closing direction when the doors are locked so as to prevent back and forth lashing of the doors and damage to the locks and doors.

A further object is to provide locks for sliding doors which shall engage the rear of such doors to secure them in closed position and embody means engageable to impart initial opening and final closing movements to the doors.

A further object is to provide locks for sliding doors which shall engage the rear of such doors to secure them in closed position and embody means engageable to impart initial opening and final closing movements to the doors wherein the locks and one of the means shall cooperate with the other of the means to restrict movement of the other means in planes parallel and at right angles to the doors.

Other objects of the invention will become clear as the description thereof proceeds.

In the drawings forming part of this specification:

Fig. 1 is an elevation of a portion of a side wall of a railway house car and the adjacent portion of a sliding door and illustrating a lock embodying the instant invention, the door being shown in closed and locked position.

Fig. 2 is a horizontal section taken on line 2—2 of Fig. 1.

Fig. 3 is a horizontal section taken on line 3—3 of Fig. 1.

Fig. 4 is a vertical section taken on line 4—4 of Fig. 1, portions of the opening and closing mechanism of the lock being shown in disengaged position in full lines and in engaged relationship in dot and dash lines.

In the drawings numeral 10 designates a portion of a side wall of a railway house car lying adjacent to the rear edge of a door opening 11 formed in the side wall. The side wall embodies a rear door post 12 which has an outer rearwardly extending flange 13 to which the metallic sheathing 14 of the side wall is secured as by means of rivets. The door post 12 is flanged inwardly as indicated at 15 and then forwardly to provide a flange 16 which is parallel to flange 13 and to the side wall 10.

2

The flange 16 is turned outwardly to provide a flange 17 contiguous with the rear edge of the door opening 11. The flange 16 carries a substantially channel-shaped member 18 which is secured to the flange 16 as by means of rivets.

The door opening 11 is adapted to be closed by a sliding door 19 which may be mounted upon the car in any desired manner. The structure of the door and means for mounting it upon the car are both well known.

10 For the purpose of the instant invention it may be stated that the door embodies a corrugated metallic panel 20, the rear vertical margin of which is reinforced by means of a substantially W-shaped member 21 and a backing plate 22 associated with the metallic panel to provide a substantially tubular construction. The rear edge of the reinforcing member 21 is flanged as indicated at 23 so as to cooperate with a spark strip 24 secured to the flange 17 of the door post as by means of rivets.

20 In accordance with the instant invention a lock is provided for securing the door in closed position by cooperation with the rear portion of the door. In the illustrated embodiment of this lock a bracket 25 is secured to the rear portion of the door as by means of rivets 26 which extend through the bracket, the metallic panel 20 and a reinforcing member 27 disposed within one of the corrugations of the panel. As shown in Fig. 2 of the drawings the bracket follows the contour of the substantially W-shaped door reinforcing member 21. The rear edge of the door bracket 25 is provided with a downwardly and inwardly inclined recess 28 formed in part by a rearwardly extending flange 29. The flange 29 is turned outwardly and rearwardly as shown at 30 and is provided with a seal slot 31.

25 A bracket 32 preferably in the form of a casting is secured to the door post 12 in the corner provided by the angularly related flanges 15 and 16 of the door post. The upper portion of the bracket is angular in cross section and embodies an outwardly extending flange 33 and a flange 34 which is parallel to the side wall. Flange 34 extends downwardly from a horizontal flange 35 at the top of the bracket which connects the vertical flanges 33 and 34 until it merges into an angular horizontal flange 35. Below the flange 35 the bracket 32 embodies a wall 36 which lies parallel to the side wall of the car. The wall 36 is reinforced by means of an outwardly extending rib 37 which merges into a horizontal flange 38 formed at the bottom of the bracket 32 and connecting rib 37 and outwardly extending flange 33. A pin 39 extends through the upper horizontal flange 35 and the lower horizontal flange 38 to which it is secured as by means of welding.

30 The pin 39 extends through a boss 40 formed in a locking member 41 so as to support the locking member for vertical sliding and horizontal swinging movements. The end of the locking member opposite the boss 40 is inclined similar to the inclined recess formed in the door bracket 25 as indicated at 42. When the member 41 is in locking engagement with the door bracket 25 the end 42 of the locking member is received within the recess 28 of the door bracket. The locking member 41 is provided with a reinforcing rib 43 the intermediate portion of which is spaced from the locking member so as to provide a seal slot 44 through which a seal (not shown) is adapted to extend. A lug 45 depends from the lower edge of the locking member 41. A lug 46 extends forwardly from the upper portion of rib 37 of the bracket 32. Lug 46 is spaced from flange 16 of the door post as shown in Fig. 3 of the drawings so as to permit the lug 45 of the locking member 41 to be disposed between the lug 46 and the flange 16.

35 A bracket 32 preferably in the form of a casting is secured to the door post 12 in the corner provided by the angularly related flanges 15 and 16 of the door post. The upper portion of the bracket is angular in cross section and embodies an outwardly extending flange 33 and a flange 34 which is parallel to the side wall. Flange 34 extends downwardly from a horizontal flange 35 at the top of the bracket which connects the vertical flanges 33 and 34 until it merges into an angular horizontal flange 35. Below the flange 35 the bracket 32 embodies a wall 36 which lies parallel to the side wall of the car. The wall 36 is reinforced by means of an outwardly extending rib 37 which merges into a horizontal flange 38 formed at the bottom of the bracket 32 and connecting rib 37 and outwardly extending flange 33. A pin 39 extends through the upper horizontal flange 35 and the lower horizontal flange 38 to which it is secured as by means of welding.

40 The pin 39 extends through a boss 40 formed in a locking member 41 so as to support the locking member for vertical sliding and horizontal swinging movements. The end of the locking member opposite the boss 40 is inclined similar to the inclined recess formed in the door bracket 25 as indicated at 42. When the member 41 is in locking engagement with the door bracket 25 the end 42 of the locking member is received within the recess 28 of the door bracket. The locking member 41 is provided with a reinforcing rib 43 the intermediate portion of which is spaced from the locking member so as to provide a seal slot 44 through which a seal (not shown) is adapted to extend. A lug 45 depends from the lower edge of the locking member 41. A lug 46 extends forwardly from the upper portion of rib 37 of the bracket 32. Lug 46 is spaced from flange 16 of the door post as shown in Fig. 3 of the drawings so as to permit the lug 45 of the locking member 41 to be disposed between the lug 46 and the flange 16.

A substantially goose-neck shaped member 47 depends from the horizontal flange 38 of the bracket 32. The member 47 is adapted to extend through an eye 48 formed in the upper end of an opening and closing lever 49 which is thereby suspended from the member 47 for swinging movement in a plane substantially parallel to the side wall and in a plane at an angle to the side wall. The lever 49 is provided with an elongated opening 50 disposed below the eye 48. A lug 51 depends from the door bracket 25 and is adapted to extend through the eye 50 when it is desired to impart initial opening and final closing movement to the door. It will be observed from Fig. 1 of the drawings that the lug 51 partially overlaps the lever 49 so as to restrict the outward swinging movement of the lever when it is suspended from the member 47. Also to prevent swinging movement of the lever 49 parallel to the side wall when the lever is suspended lugs 52 and 53 are provided which lie on opposite sides of the lever 49.

In Fig. 2 of the drawings the door is illustrated in closed and locked position. At this time the end or nose 42 of the locking member 41 is received within the recess 28 of the door bracket 25 so as to prevent movement of the door in opening direction. However, as a result of the inclination of the recess 28 and nose 42 of the locking member and of the fact that the locking member is slideable vertically on the pin 39 the locking lever may be lowered by the action of gravity in the event that the door is not fully closed and moves in closing direction. This lowering movement of the locking member takes up the slack which is created by the movement of the door in closing direction so as to automatically re-establish engagement between the locking member and the door bracket. Hence while the door may move in closing direction if it is not fully closed the noted cooperation between the locking member and the lock bracket prevents movement of the door in opening direction and therefore undesirable lashing of the door.

When it is desired to open the door the seal (not shown) which extends through the seal slots 31 and 44 is removed and the locking member 41 is moved vertically upward on the pin 39. This movement is continued until the lug 45 on the locking member lies above the lug 46 formed on the bracket 32. The locking member 41 is swung inwardly toward the car side and then lowered on the pin 39 until the lug 45 lies behind the lug 46. When this relationship between these lugs is established the locking member is positively retained in such position that it will not interfere either with the opening or closing movement of the door.

In order to impart initial opening movement to the door the lever 49 is swung outwardly so as to be disengaged from the lugs 52 and 53 and is then engaged with the lug 51 by passing the elongated slot 50 over the lug 51. The door may then be started in opening direction and after this occurs the lever is disengaged from the lug 51 and dropped to its inoperative position between the lugs 52 and 53. The door may then be fully opened.

In order to close and lock the door it is first moved across the door opening 11 into substantially the position shown in Fig. 2 of the drawings. The locking member 41 is then raised so as to disengage lug 45 from lug 46 after which it is swung outwardly about the pin 39 and the nose of the locking member is engaged in the recess of the door bracket. In this position the locking member is prevented from swinging outwardly by flange 29 and inwardly by rib 37. If necessary, the lever 49 is engaged with the lug 51 in order to impart final closing movement to the door and permit the above described engagement between the locking member and the door bracket. After this engagement has been established a seal is passed through the seal slots 31 and 44 in order to seal the door in closed position. If at this time the door is not fully closed it may move in closing direction and the

slack created by such movement will be automatically absorbed by the door lock.

It will be apparent that numerous changes and modifications in the details of the invention will be clear to those skilled in the art. It is intended, therefore, that all such changes and modifications be comprehended within this invention which is to be limited only by the scope of the claims appended hereto.

I claim:

1. In a railway house car having a side wall provided with a door opening and a sliding door having front and rear portions adapted to close the door opening, a lock bracket secured to the rear portion of said door between the upper and lower edges thereof, said bracket having a vertical rearwardly facing recess, a supporting bracket secured to said side wall, a locking member, and means mounting said locking member on said supporting bracket for vertical sliding and horizontal swinging movements, said locking member extending into said recess in abutting relationship with said lock bracket to prevent rearward opening movement of said door.
2. In a railway house car having a side wall provided with a door opening and a sliding door having front and rear portions adapted to close the door opening, a lock bracket secured to the rear portion of said door between the upper and lower edges thereof, said bracket having a vertical rearwardly facing recess, a supporting bracket secured to said side wall, a locking member, and means mounting said locking member on said supporting bracket for vertical sliding and horizontal swinging movements, said locking member extending into said recess in abutting relationship with said lock bracket to prevent rearward opening movement of said door, said recess being formed in part by a rearwardly extending flange, said flange having outward overlapping relationship with said locking member when the latter is in said abutting relationship with said lock member.
3. In a railway house car having a side wall provided with a door opening and a sliding door having front and rear portions adapted to close the door opening, a lock bracket secured to the rear portion of said door between the upper and lower edges thereof, said bracket having a downwardly and rearwardly inclined recess, a supporting bracket secured to said side wall, a locking member, and means mounting said locking member on said supporting bracket for vertical sliding and horizontal swinging movements, said locking member having a similarly inclined portion extending into said recess in abutting relationship with said lock bracket to prevent rearward opening movement of said door.
4. In a railway house car having a side wall provided with a door opening and a sliding door having front and rear portions adapted to close the door opening, a lock bracket secured to the rear portion of said door between the upper and lower edges thereof, said bracket having a vertical rearwardly facing recess, a supporting bracket secured to said side wall, a locking member, and means mounting said locking member on said supporting bracket for vertical sliding and horizontal swinging movements, said locking member extending into said recess in abutting relationship with said lock bracket to prevent rearward opening movement of said door, means on said supporting bracket, and means on said locking member adapted to engage said first mentioned means when said locking member has been disengaged from said lock bracket to prevent outward swinging movement of said locking member.
5. In a railway house car having a side wall provided with a door opening and a sliding door having front and rear portions adapted to close the door opening, a lock bracket secured to the rear portion of said door between the upper and lower edges thereof, said bracket having a downwardly and rearwardly inclined recess, a supporting bracket secured to said side wall, a locking member, means mounting said locking member on said sup-

porting bracket secured to said side wall, a locking member having movements, said locking member having a similarly inclined portion extending into said recess in abutting relationship with said lock bracket to prevent rearward opening movement of said door, a lug extending from said supporting bracket and a lug extending from said locking member, said latter lug being adapted to lie behind said former lug after disengagement of said locking member from said lock bracket to prevent outward swinging movement of said locking member.

6. In a railway house car having a side wall provided with a door opening and a sliding door having front and rear portions adapted to close the door opening, a lock bracket secured to the rear portion of said door between the upper and lower edges thereof, said bracket having a downwardly and rearwardly inclined recess, a supporting bracket secured to said side wall, a vertical pin carried by said supporting bracket and a locking member mounted on said pin for vertical sliding and horizontal swinging movements, said locking member having a similarly inclined portion extending into said recess in abutting relationship with said lock bracket to prevent rearward opening movement of said door.

7. In a railway house car having a side wall provided with a door opening and a sliding door having front and rear portions adapted to close the door opening, a lock bracket secured to the rear portion of said door between the upper and lower edges thereof, said bracket having a downwardly and rearwardly inclined recess, a supporting bracket secured to said side wall, a vertical pin carried by said supporting bracket, a locking member mounted on said pin for vertical sliding and horizontal swinging movements, said locking member having a similarly inclined portion extending into said recess in abutting relationship with said lock bracket to prevent rearward opening movement of said door, a lug extending downwardly from said locking member and a lug extending forwardly from the upper portion of said supporting bracket in spaced relationship to said side wall, said locking member being slidable upwardly on said pin to effect disengagement thereof from said lock bracket, said locking member being swingable inwardly about said pin toward said side wall and slidable downwardly on said pin to dispose said lug on said locking member behind said lug on said lock bracket to prevent outward swinging movement of said locking member.

8. In a railway house car having a side wall provided with a door opening and a sliding door having front and rear portions adapted to close the door opening, a lock bracket secured to the rear portion of said door between the upper and lower edges thereof, said bracket having a downwardly and rearwardly inclined recess, a supporting bracket secured to said side wall, a locking member, means mounting said locking member on said supporting bracket for vertical sliding and horizontal swinging movements, said locking member having a similarly inclined portion extending into said recess in abutting relationship

with said lock bracket to prevent rearward opening movement of said door, a lug depending from said lock bracket, a lever suspended from said supporting bracket for swinging movement parallel to and away from said side wall, said lever being engageable with said lug to impart initial opening and final closing movements to said door and lugs extending downwardly from said supporting bracket on opposite sides of said lever to prevent swinging movement thereof parallel to said side wall.

9. In a railway house car having a side wall provided with a door opening and a sliding door having front and rear portions adapted to close the door opening, a lock bracket secured to the rear portion of said door between the upper and lower edges thereof, said bracket having a downwardly and rearwardly inclined recess, a supporting bracket secured to said side wall, a locking member, means mounting said locking member on said supporting bracket for vertical sliding and horizontal swinging movements, said locking member having a similarly inclined portion extending into said recess in abutting relationship with said lock bracket to prevent rearward opening movement of said door, a lug depending from said lock bracket, a lever suspended from said supporting bracket for swinging movement parallel to and away from said side wall, said lever being engageable with said lug to impart initial opening and final closing movements to said door and lugs extending downwardly from said supporting bracket on opposite sides of said lever to prevent swinging movement thereof parallel to said side wall, said first mentioned lug having outwardly overlapping relationship with said lever to limit outward swinging movement thereof.

10. In a railway house car having a side wall provided with a door opening and a sliding door having front and rear portions adapted to close the door opening, a lock bracket secured to the rear portion of said door between the upper and lower edges thereof, said bracket having a vertical rearwardly facing recess, a supporting bracket secured to said side wall, a locking member, and means mounting said locking member on said supporting bracket for vertical sliding and horizontal swinging movements, said locking member extending into said recess in abutting relationship with said lock bracket to prevent rearward opening movement of said door, said recess being formed in part by a rearwardly extending flange, said supporting bracket having an outwardly extending rib, said locking member extending between said latter flange and rib when in locking position.
